UNITED STATES PATENT OFFICE.

EDGAR W. ANTHONY, OF BOSTON, MASSACHUSETTS.

DESIGN FOR A HEATING-STOVE.

SPECIFICATION forming part of Design No. 17,641, dated August 23, 1887.

Application filed November 10, 1883. Serial No. 111,479. Term of patent 14 years.

To all whom it may concern:

Be it known that I, EDGAR W. ANTHONY, of Boston, in the county of Suffolk and State of Massachusetts, a citizen of the United States, have invented and produced a certain new and useful Design for Heating-Stoves, of which the following is a full, clear, and exact description, reference being had to the accompanying photographs, in which—

- 10 No. 1 is a photograph of the stove as a whole. No. 2 is a photograph of the top thereof. No. 3 is a photograph of the upper base-plate.
15 The features of the design are well illustrated by the photographs.
15 Commencing at the base, the stove-leg has as its features the double scroll *a*, with the upward-extending spreading portions *a'* and the rosettes *a''*. Each side of the base portion has an ornamental panel, *b*, which is well represented in the photograph, and also the corners *c*, the features of which are the spreading base, the ornamental section *c'*, the horizontal beads with vertical lines upon the portion of the corner between the beads, represented 25 either by outwardly-extending ribs or by recesses.

The design for the ash-pit door is well illustrated in the photograph, and consists in a series of sunken panels. These panels are 30 formed by raised portions or ribs which extend across the door horizontally and vertically, intersecting each other to form the panels.

The design for the upper surface of the upper base-plate is well shown in the photograph No. 3, and the scroll-work in the corners, aside from the proportion in plan and elevation of the plate, comprises the essential features. The foot-rail is also well illustrated 35 by the photograph. It has a rounded upper surface and a scalloped lower edge.

The frame-work about the upper door is another feature of the design, and is well illustrated by the photographs. This door is also 40 well shown in the photograph, and its division into squares and the introduction of the corner and central scroll are well represented by it. The portions not represented by scroll-work are to be closed by sheets of mica or 45 other transparent material. Below the door-frame is an ornamental piece, which has the

design and general configuration shown in the photograph.

The portion of the design *d* immediately below the upper or top plate is well represented 55 by the photograph. The top plate has the proportion and general configuration represented in photograph No. 2, and is ornamented as therein shown.

The shape and design of the cover are also 60 represented in photographs Nos. 1 and 2, as is also that of the ornamental panel *e*, which is supported by the cover.

The general proportion which each ornamental plate and part of the stove bears to all 65 the others is well represented in photograph No. 1, and the general character of the design as constituted by the use of square and circular figures. The line-work is also well shown in said photograph. 70

Having thus fully described my design, I claim and desire to secure by Letters Patent of the United States—

1. In a design for a stove, the front door comprising horizontal and vertical bars, spaces 75 for mica or transparent lights, and a central rosette, and a rosette at each corner of the door, as illustrated and described.

2. In a design for a heating-stove, the top plate having an inclined ornamented upper 80 surface with semicircular figures or rosettes, and a dome-section having a flat or substantially flat top and rounded ribs extending from the edge of the flat section to the lower edge of the dome and increasing in width as they 85 are curved upward, as illustrated and described.

3. In a design for a heating-stove, the ash-pit door having the horizontal bars and vertical bars with alternating rectangular and oval 90 openings, as illustrated and described.

4. In a design for a heating-stove, a stove-leg having a rosette upon each side near the top, and the fluted work narrowing and ending in scrolls at each side of the leg at the bottom, as 95 illustrated and described.

5. In a design for a heating-stove, the base-section having rounded corners with ornamental bases and vertically-fluted sections, as 100 illustrated and described.

6. A stove-top having a flat plate or panel surrounded by a border having a rounded edge

Accu

and supported upon four pillars or posts, as illustrated and described.

7. In a design for a heating-stove, the curved body, an ornamental door-frame, a door set upon said body, and an ornamental plate or panel immediately below said door-frame and having the curved body extending from each edge thereof, as illustrated and described.

8. The herein-described design for heating-

stove, the same comprising a projecting base, a circular body, and a circular top having an inclined plate surmounted by an ornamental dome, the whole having the shape and ornamentation shown, as illustrated and described.

EDGAR W. ANTHONY.
